AUTOMOBILE TOP STAY STRAP

Filed April 25, 1922

Fig. 1.

INVENTOR
George S. Avey,
BY
Cornelius C. Billings
his ATTORNEY

UNITED STATES PATENT OFFICE.

GEORGE S. AVEY, OF CINCINNATI, OHIO.

AUTOMOBILE TOP STAY STRAP.

Application filed April 25, 1922. Serial No. 556,398.

To all whom it may concern:

Be it known that I, GEORGE S. AVEY, a citizen of the United States, and a resident of Cincinnati, county of Hamilton, State of Ohio, have invented certain new and useful Improvements in Automobile Top Stay Straps, of which the following is a specification.

This invention relates to a stay strap which is utilized for securing or anchoring the top or roof portion of a vehicle top to the body of the vehicle to prevent swaying and loosening of the top.

In the usual type of vehicle top which is attached to and supported on the vehicle body by ribs, a considerable strain is placed on the upper part of the top, when raised, by the pocketing of air in the rear part of the top structure when the vehicle is in motion which tends to lift or pull the top from its fastenings, and also by the swaying of the top as the vehicle is jolted sidewise, which tends to loosen the fastening of the top to the vehicle. Strap devices have been proposed for attaching the top or crossing part of the ribs to the vehicle body but these straps have not proven satisfactory as they do not provide a gradual or graduated shortening and tightening of the strap to adapt them to be used where the distance from the rib top to the vehicle body does not correspond exactly to the fixed adjustments of the strap or to adjust the strap to stretching with use. Moreover, these straps have not been of a type which may be readily attached and adjusted to the top and vehicle.

An object of the present invention is to provide an anchoring strap which may be quickly and easily attached and adjusted to a vehicle top.

Another object of the invention is to provide an anchoring strap for vehicle tops in which the use of buckles is not required and in which any desired adjustment of length and tautness may be obtained by reeving the strap to enlarge or contract loops which take up the length of the strap.

A further object of the invention is to provide an anchoring strap for vehicles which will remain in any degree of adjustment without fastening means.

With these and other objects in view, the invention comprises the strap described and set forth in the following specification and claims.

The various features of the invention are

illustrated in the accompanying drawings in which:

Fig. 1 is a side view of a strap embodying a preferred form of the invention. 60

Fig. 2 is a front view of the strap shown in Fig. 2, a modified means for securing the strap to the bow of the top being illustrated, and

Fig. 3 is a perspective view of a vehicle 65 top with the stay strap embodying my invention in place.

In the present invention an anchoring strap is provided which may be quickly and easily attached and detached and may be 70 easily adjusted to any desired length or tautness. To this end a strap of a suitable flexible material is folded or reeved through suitable eyelets to form a series of loops which span the distance between the members to be anchored and other loops which may be enlarged or contracted at the expense of the spanning loops in such a manner as to lengthen or shorten the effective 75 distance between the objects to be anchored. 80 The strap is preferably formed in three loops, two of which span the distance between the members to be anchored and the third of which spans only a portion of this distance and, by being enlarged with a length of strap drawn from the spanning 85 loops, may shorten the spanning loops and reduce the length which they span. For this purpose, one end of the strap is attached to an end eyelet and the other end is reeved 90 through a loop holder and a middle eyelet and back through the end eyelet to form a loop, then through another end eyelet and through the middle eyelet to form a middle loop, the third or end loop being formed 95 by attaching the end of the strap to the second end eyelet. By reeving the strap back and forth through the middle eyelet the middle loop may be enlarged or contracted and the end loops accordingly contracted or 100 enlarged to shorten or lengthen the distance between loop holders through which these loops are reeved and which may be connected to the vehicle and its top.

Referring more particularly to the accompanying drawing, an end 5 of a strap 6 forming the body of a stay strap A is inserted through the opening of an end eyelet 7 and fastened by being doubled upon itself and stitched. The strap is then passed over 110 or through a loop holder 8, folded downwardly on itself and reeved through a mid-

dle eyelet 9. It is then folded upwardly and reeved through the end eyelet 7 to form an end loop 10. The length of strap extending through the eyelet 7 is then folded downwardly, reeved through a second end eyelet 11 and folded upwardly to the middle eyelet. It is then passed through the middle eyelet to form a middle loop 12. An end loop 13, which with the loop 10 spans the distance to be anchored, is formed by folding the strap downwardly, reeving it through a lower loop holder 14, folding it upwardly and attaching it to the end eyelet 11 in the manner in which the other end is attached to the upper end eyelet 7.

The loop holders 8 and 14 may be of any standard or suitable construction. The upper loop holder is preferably formed of a length of metal which is bent to form an offset length 15 over which the end loop of the strap is reeved and end lengths 16 and 17 in which openings 18 are formed for attaching the holder to the ribs of the vehicle top. The loop holder may be permanently attached to the rib by means of screws 19 passed through the openings 18 as indicated in Fig. 2, or may be detachably attached by means of depending hooks 20 extending downwardly from the ribs as shown in Fig. 2. The lower loop holder 14 is provided with a hook 21 which may be inserted through the eye of an eye-bolt 22 on the body of the vehicle. This hook may be easily detached or inserted when the vehicle top is to be lowered or raised. It is immaterial whether the strap be entirely removed although a permanent attachment such as that of Fig. 2 is preferable.

The length between the loop holders 8 and 14 may be shortened and the strap tautened by grasping the length of strap common to the end loops and middle loop, indicated in the drawings by the numerals 23 and 24, and pulling a portion of strap from the end loops through the middle eyelet to enlarge the middle loop. It will be apparent that for every length of strap pulled through the middle eyelet in this manner one-half is used in lengthening the common loop lengths 23 and 24 and the other half passes to an outer length 25 of the middle loop. As the total length of the end loops 10 and 13 determine the distance between the loop holders 8 and 14 it will be apparent that, as the middle loop and the length 25 are lengthened, the end loops 10 and 13, and accordingly the distance between the loop holders 8 and 14, is shortened and the strap tautened.

Each change in the length of the strap involves a passage of strap through each of the loop holders 8 and 14 and the middle eyelet 9 which creates a comparatively large frictional resistance to the loosening of the strap since the full tension of the strap is

exerted at these places. As only a part of the tension on the strap is unbalanced between the strands of the loops in such a manner as to tend to draw the strap from one loop to the other, the frictional resistance to its passage is sufficiently great to hold the strap in its tautened or adjusted position without the necessity of fastening means. In attaching the strap it therefore is only necessary to hook the hook 21 through the eyebolt 22 and pull on the lengths of strap 23 and 24. Similarly when the strap is to be removed it is only necessary to loosen the lengths 23 and 24 and unhook the hook from the eyebolt 22. If the upper loop holder 8 is detachable its attachment and detachment may be very readily accomplished but it is preferably attached permanently to the rib top.

It will be noted also that the tension of the strap is divided into a number of strands each of which carries only a part of the tension and that greater strength is obtained than if only one strand were used.

Having described the invention, what I claim and desire to secure by Letters Patent is:

1. An extensible stay of the type described which comprises a strap reeved to form spanning loops extending between certain points and an additional loop having strap sections common to two of said spanning loops, said loops being arranged so that said additional loop may be enlarged at the expense of said spanning loops.

2. An extensible stay of the type described which comprises a series of eyelets, a strap attached at its ends to the end eyelets of said series and reeved through an intermediate eyelet to form a middle loop, said middle loop portion being reeved through said end eyelets to form end loops, and loop holders for said end loops, said end loops spanning the distance between said loop holders.

3. A device of the kind described which comprises a series of eyelets, a strap attached at its ends to the end eyelets of said series and reeved through an intermediate eyelet and said end eyelets to form a series of spanning and intermediate loops and loop holders in said end spanning loops, said spanning and intermediate loops being expandable and contractible at the expense of each other to increase or decrease the length of the span.

4. An extensible stay of the type described which comprises a series of eyelets, a pair of loop holders, and a strap having one end attached to one of said eyelets and reeved successively through a loop holder, a middle eyelet, said first named eyelet, a third eyelet, said middle eyelet, a second loop holder and having the remaining end attached to said third eyelet, thereby forming three inter-

connected loops which may be relatively enlarged and contracted to vary the distance between said loop holders.

5. An extensible stay of the type described which comprises a single strap folded upon itself to form three adjustable loops, one of which is disposed centrally of the other two and in which the parts of said strap which

form portions of the center loop also form respectively a portion of each end loop, and means carried by each end loop for supporting the stay strap in operative position.

In witness whereof I have hereunto set my hand this 21st day of April, 1922.

GEO. S. AVEY.
